[57] **ABSTRACT**

The storage stability of tetrakis nickel compounds, such as tetrakis (triorganophosphite) nickel compounds, can be increased by storing said compounds under a protective blanket selected from alcohols and aliphatic hydrocarbons.

6 Claims, No Drawings

STORAGE STABILITY OF TETRAKIS NICKEL COMPOUNDS

BACKGROUND OF THE INVENTION

This invention relates to a method for improving the storage stability of tetrakis nickel compounds. More particularly this invention relates to a method for improving storage stability of tetrakis (triorganophosphite) nickel compounds.

It is known that an organonickel compound can be reacted with a triorganophosphorous compound to yield a tetrakis (triorganophosphite) nickel compound, which can be precipitated and recovered as a solid product, useful as a polymerization catalyst. It has been found that upon storage, the tetrakis nickel compounds tend to decompose badly after periods of more than a few days, even when stored under a blanket of nitrogen.

SUMMARY OF THE INVENTION

It has now been found that solid tetrakis (triorganophosphite) nickel compounds, contaminated with residual triorganophosphite compounds, can be stored for extended periods of time when stored in a protective atmosphere selected from alcohols and aliphatic hydrocarbons.

In the preparation of a tetrakis (triorganophosphorous) nickel compound, such as described and claimed in U.S. Pat. Nos 3,152,158 and 3,328,443, a nickel compound can be reacted with a triorganophosphorous compound, and the reaction product comprising complexed zerovalent nickel can be precipitated by pouring the mixture into an inert non-solvent. The precipitated product can be recovered by filtration and is useful as a catalyst. U.S. Pat. No. 3,243,468 describes and claims the use of such tetrakis nickel compounds in the polymerization of various monomers, such as butadiene.

The tetrakis (triorganophosphite) nickel compounds prepared as described above have been found to be quite stable in a completely pure state. It has further been found that when contaminated with relatively small amounts of residual triorganophosphite compounds, the tetrakis nickel compounds tend to be quite unstable during storage, starting to decompose almost immediately, for example within an hour, even when stored under a blanket of nitrogen. One way of obviating or overcoming this problem is to work up and purify the tetrakis nickel compounds to a point that there is no remaining residual triorganophosphite material left as a contaminant. Unfortunately however, this procedure is time consuming and expensive and yields no real benefit since the presence of small amounts of triorganophosphite material does not effect the utility of the tetrakis (triorganophosphite) nickel compounds as polymerization catalysts. As an alternative to the scrupulous scrubbing of the tetrakis nickel compounds to remove all trace of triorganophosphorous contaminants, it has been found that storage stability of the solid tetrakis (triorganophosphorous) nickel compounds can be improved by storing the material in accordance with this invention.

Broadly, the improved storage stability can be obtained by storing tetrakis (triorganophosphite) nickel, which is contaminated with triorganophosphite, under a protective blanket consisting essentially of an inert non-solvent for said tetrakis (triorganophosphite) nickel. As used herein, the term "non-solvent" refers to compounds which will dissolve less than about 1 percent by weight of the tetrakis (triorganophosphorous) nickel compound while the term "solvent" is meant to include compounds in which more than about 1 percent by weight of the tetrakis nickel compounds are soluble. Characteristics of the non-solvents which are useful in the scope of this invention are that they be appreciably miscible with triorganophosphorous contaminant but that the tetrakis nickel product be insoluble therein. Another characteristic of the non-solvent is that it be easily and substantially completely removable from the stored product. Thus, generally, a non-solvent having a low viscosity is more desirable than one having a high viscosity. Volatility is another factor to be con-

sidered in choosing a non-solvent. Since the tetrakis nickel product is generally stored at ambient temperature, the non-solvent vapor pressure is desirably not excessive at these temperatures. Broadly, the boiling point of the non-solvent can range from about 20° C. to about 300° C. with a preferred range of from about 50° to about 200° C. The non-solvent will of course be inert with respect to both the reactants and the products and be inert to the surrounding atmosphere. Since this atmosphere is usually air, the non-solvent is desirably not readily oxidized under ambient conditions when the storage container is opened, as for example for the periodic removal of portions of the tetrakis nickel compounds.

As indicated above, the alcohols are a preferred class of non-solvents. The alcohols can be primary, secondary or tertiary, and can be monohydric or polyhydric. Preferred alcohols are alkanols having up to about 14 carbon atoms and include for example methanol, ethanol, propanol-1, 2-methylpropanol-1, butanol-1, pentanol-1, 2-ethyl-butanol-1, cyclohexanol, octanol-1, dodecanol-1, ethylene glycol and triethylene glycol. Liquid alkanols are especially preferred. Mixtures of these alcohols can also be used. Insofar as the liquid alkanols are commercially available and inexpensive, they are especially preferred.

In addition to the alcohols, it has been found that alkanes are another preferred class of non-solvents. The preferred saturated aliphatic hydrocarbons are those which are liquid at ambient temperature. Thus, generally, those saturated aliphatic hydrocarbons having from about five to about 14 carbon atoms are preferred with the c_5 to c_7 hydrocarbons, such as hexane or heptane, being particularly preferred. The saturated aliphatic hydrocarbons can be used either alone or in combination with other saturated aliphatic hydrocarbons and can be either straight or branched chain.

As a general proposition, hydrocarbons other than the saturated aliphatic hydrocarbons, oxygenated hydrocarbons other than the alcohols and alcohol ethers, halogenated hydrocarbons, heterocyclic compounds, aromatic hydrocarbons, etc., can be classified as solvents for the tetrakis nickel compound and are not useful under the conditions set forth herein. These latter compounds can be used as recrystallization solvents, if recrystallization is needed or desired for the crude tetrakis nickel compound. Solvents are not desirable agents for contacting the tetrakis nickel compounds in storage insofar as it has been found that a solution of the tetrakis nickel compound, when exposed to even traces of air or oxygen, decomposes rapidly in a very short time.

The process of this invention is useful regardless of the structure of the triorganophosphite contaminant or the triorganophosphite ligand in the nickel complex. Examples of well-known and useful phosphite contaminants and ligands include tri(2-ethyl-hexyl) phosphite, tri(p-methoxyphenyl) phosphite, triphenylphosphite, trioctylphosphite, triethylphosphite and tri(methoxymethyl) phosphite.

One method of precipitating the tetrakis nickel compound from the reaction mixture and thereafter storing it, is to use one non-solvent as a precipitant and another non-solvent as the atmosphere to store the filtered product. The preferred practice, however is to use the same non-solvent for both functions. This, of course, avoids the inconvenience and cost of multiple steps. When the tetrakis nickel compound is isolated from its reaction mixture, as by precipitation using an inert non-solvent, the isolation can be carried out in any convenient manner, such as by filtration using known and accepted methods and equipment. The isolated product, in the form of a filter cake, can be washed with a fresh portion of the non-solvent. While not essential, this is a desirable intermediate step insofar as it is useful to remove at least part of the triorganophosphite contaminant from the precipitated tetrakis nickel compound. Additional filtration can, of course, be used to remove the wash liquid.

The quantity of non-solvent used as an atmosphere to protect the isolated tetrakis nickel compounds is broadly that amount needed to effectively shield the product from an ox-

idizing atmosphere. Since the catalyst product is substantially insoluble in the non-solvent, a large excess of non-solvent can be used. There is, however, no significant benefit to be derived from the use of a large excess and, in fact, it is preferred to use that amount of non-solvent which just covers the surface of the product.

It has been found that moisture frequently can be a contributing factor to the decomposition of the catalyst and it is therefore desirable to maintain a low level of moisture in the stored product and its immediate atmosphere. This can be conveniently accomplished by using a product prepared under conditions minimizing contact with atmospheric moisture, such as by using an anhydrous non-solvent and by storing the tetrakis nickel compound together with the non-solvent in a substantially airtight container.

DESCRIPTION OF THE PREFERRED EMBODIMENTS

EXAMPLE I

Tetrakis (triphenylphosphite) nickel was prepared according to the following method: nickel acetylacetone dihydrate (21.76 lbs., 0.0745 mole) was dissolved in benzene (161.25 lbs.), and the solution was azeotropically distilled to remove water. The resultant solution was used. Triphenylphosphite (94.6 lbs., 0.305 mole) was added, with mild agitation. The temperature of the mixture was 8° C. Triethyl aluminum (18.75 lbs., 0.165 mole) in 75 lbs. dry benzene was added, with mild agitation, over a period of about one hour. During this addition period, the reaction temperature was allowed to rise to 16° C. Then, over a period of 30 minutes the reactor temperature was raised to 40° C. The reactor contents were poured, over a period of 30 minutes, into a tank containing 401 lbs. of methanol. A precipitate of tetrakis (triphenylphosphite) nickel was formed. The product was separated by a centrifuge filter, and the alcohol-wet filter cake was removed from the centrifuge. The cake was slurried with additional methanol, and the mixture was filtered. The washed and filtered product was then air-dried and stored in a polyethylene bag, under a dry nitrogen atmosphere. The product was a white powder. The product obtained above was determined to be substantially free of triphenylphosphite. The following evaluations were performed: tetrakis nickel catalyst prepared above (10 grams) was placed in clean 4 oz. flint glass bottle, equipped with a screw cap, and was treated with various additives. All test specimens were periodically opened to the atmosphere. Bottle 1 contained 0.5 ml. water; bottle 2 contained 0.5 ml. water plus 1 ml. triphenylphosphite; bottle 3 contained 1 ml. triphenylphosphite; bottle 4 contained 20 ml. methanol; and bottle 5 contained 20 ml. methanol plus 1 ml. triphenylphosphite. The capped bottles were opened three times a week to assure an adequate exposure to air and oxygen. Visual examinations were made at the end of two weeks and at the end of four weeks. The results are shown in Table 1.

methanol, washing several times with methanol and drying at room temperature in a nitrogen atmosphere. 15 grams of this recrystallized tetrakis (triphenylphosphite) nickel was slurried with a mixture of 50 ml. methanol and 1.5 grams triphenylphosphite. The methanol was evaporated by a nitrogen stream at room temperature, leaving white crystals of the tetrakis compound coated with triphenylphosphite. This product was put in a one liter beaker, open to air and ambient humidity. Determinations of acid-soluble divalent nickel concentration were made at the intervals indicated below as a means of determining the extent of decomposition. The results are summarized in Table 2 below.

TABLE 2

Days of Open Storage	Ni ⁺⁺ Concentration	%Decomposition
20	3	533 ppm
	5	1042 ppm
	7	1567 ppm
	11	17,100 ppm (1.71%)

The percent decomposition was calculated on the basis that the tetrakis nickel catalyst contained 4.51 percent nickel. It can be seen from the above that after eleven days of open storage there has been substantial and significant decomposition.

EXAMPLE III

A variety of liquid organic compounds was tested for protective activity toward the tetrakis nickel compound by the following procedure:

In a 1 oz. glass bottle, fitted with a screw cap, was placed 1 gram of the tetrakis (triphenylphosphite) nickel, prepared in Example I above, together with 0.1 ml. triphenylphosphite and 2 ml. of the test liquid indicated below. The capped sample bottles were opened twice a week, and the following visual observations were made, as summarized in Table 3 below.

TABLE 2

Test Liquid	Observed sample color after 2 wks.	Observed sample color after 5 months
Methanol	White	White
Ethanol	White	White
Propanol-1	White	White
Butanol-1	White	White
2-Methyl-propanol-1	White	White
Pentanol-1	White	White
2-Ethyl-butanol-1	White	White
Cyclohexanol	White	White
Ethylene glycol	White	White
Triethylene glycol	White	White
Hexane	White	White
Ethyl acetate	Light Grey	Light Grey
Amyl acetate	White	Grey
Acetone	Grey	Green

TABLE 1

Bottle	Additive	Description of bottle contents		
		At start	After 2 weeks	After 4 weeks
1.....	Water.....	White solid.....	White solid.....	White solid.....
2.....	Water plus triphenylphosphite.....	do.....	Greenish paste.....	Yellow-green paste.....
3.....	Triphenylphosphite.....	do.....	Light green solid.....	Yellow-green solid.....
4.....	Methanol.....	do.....	White solid, with faint supernatant liquid.....	White solid, with faint supernatant liquid.....
5.....	Methanol plus triphenylphosphite.....	do.....	do.....	do.....

It can be seen from the above results that there was essentially no difference between the results obtained with methanol and methanol plus triphenylphosphite. Water, on the other hand, in connection with triphenylphosphite, yielded very poor results.

EXAMPLE II

A portion of the product prepared in Example I was recrystallized by dissolving in benzene, precipitating in

70	Methyl ethyl ketone	Light Green	Green
	Propionic acid	White	Light Grey
	Butyl chloride	Grey	Green
	Carbon tetrachloride	Orange	Orange
	Dimethyl sulfoxide	White	Light Green
	Dimethyl formamide	Light Green	Light Green
	Pyridine	Brown	Brown Liquid
	Aniline	Grey-Green	Dark Green
	Benzene	Green-Brown	Green-Brown
	1,5-Cyclooctadiene	Brown	Brown paste

Filtration of the sample covered with methanol gives a tetrakis nickel catalyst that is active in the preparation of, for example, cyclooctadiene. The other alcohols and aliphatics can also be removed in a similar fashion to furnish equivalent results.

Therefore I claim:

1. Method of increasing the storage stability of previously prepared and isolated tetrakis (triorganophosphite) nickel which is contaminated with triorganophosphite comprising storing said contaminated tetrakis (triorganophosphite) nickel under a protective blanket consisting essentially of an inert non-solvent for said tetrakis (triorganophosphite) nickel.

2. A method according to claim 1 in which the inert non-sol-

vent is selected from alcohols and saturated aliphatic hydrocarbons.

3. A method according to claim 1 in which the alcohols are primary and have a chain length of from one to about 14 carbon atoms.

4. A method according to claim 1 in which the aliphatic hydrocarbons have a chain length of from about five to about 14 carbon atoms.

5. A method according to claim 1 in which the alcohol is methanol.

6. A method according to claim 1 in which the aliphatic hydrocarbon is hexane.
